UNITED STATES PATENT OFFICE.

FRANCES C. McDONALD, OF CHICAGO, ILLINOIS.

GARMENT-SUPPORTER.

SPECIFICATION forming part of Letters Patent No. 746,983, dated December 15, 1903.

Application filed August 26, 1903. Serial No. 170,826. (No model.)

To all whom it may concern:

Be it known that I, FRANCES C. McDONALD, a citizen of the United States, and a resident of Chicago, in the county of Cook and State 5 of Illinois, have invented new and useful Improvements in Garment-Supporters, of which the following is a full, clear, and exact description.

My present invention pertains to garment-supporters, and is in the nature of an improvement upon the device forming the subject-matter of my Patent No. 739,698, dated September 22, 1903.

It is the purpose of the present invention 15 to devise a garment-supporter particularly designed for use in retaining and securing hosiery and the like which will embody the features of durability, simplicity, and convenience.

Another object of my invention is to so correlate and combine a locking member with the frame or main body portion of the supporter that a button, stud, or similar article 20 may be securely and firmly locked by the supporter, the button being adapted to engage with a stocking or other article of clothing.

To the accomplishment of the above-re-cited ends the invention consists in the construction, combination, and arrangement of parts as is described in this specification, illustrated in the accompanying drawings, and set forth in the appended claims.

Reference is to be had to the accompanying 35 drawings, forming a part of this specification, in which similar characters of reference indicate corresponding parts in all the figures.

Figure 1 is a perspective view of a garment-supporter embodying my improvements. Fig. 2 is a face or front view of a portion of the supporter carrying the locking-tongue, and Fig. 3 is a vertical sectional view taken through my improved garment-supporter.

In the accompanying drawings, 45 designates a strap having formed a short distance above the end thereof a loop, as at 6, to which loop is designed to be secured my improved garment-supporter or retaining member.

The construction of this supporter, which is designated as a whole by *a* and which is

clearly shown in Fig. 2, comprises, essentially, a transverse tubular bar 7, designed to retain the horizontally-extending end portions 8 8 of the main body portion or frame of the supporter, said frame being formed from a single piece of wire or other suitable material, bent, approximately, centrally, as at 9, to form a relatively elongated tongue or 55 loop portion, the sides 10 10 of which are formed with shoulders 11 11 about midway the length of said sides, said shoulders serving a purpose to be hereinafter set forth. At about one-half the length of the entire body 60 portion the sides 10 10 diverge outwardly, as at 12 12, and are then bent to form the upwardly-extending arm portions 13 13, which members or arms 13 converge slightly inward to the curved or shouldered portions 14 65 70 when they again turn outward at approximately right angles to the arms 13 13, forming the loop portions 15 15, which terminate in the free ends 8 8, said ends, as above described, being inserted in and held by the 75 tubular sleeve or bar 7. It will thus be seen that each of the sides of the main body portions of the fastener is formed with a compound curved bend. Secured to the curved 80 or bent portions 12 12 at the termination of the sides 10 10 of the tongue 9 is a hinge member 16, the sides 17 17 of such member being bent or extended outwardly relative to each other to permit the engagement of the ends of said arms with the body portion of 85 the loop. The sides 17 17 of the hinge member are curved or bent upwardly at their end portions 18 18 and terminate in the cross-bar 19, which bar is slightly curved or bent inwardly to enable it to securely engage with 90 the shank of a button or the like.

From the above description of the locking member it will be seen that it is approximately U-shaped in form, with the cross-bar set at an angle to the parallel arms of the 95 member. When in use, the tongue portion 9 of the fastening member is designed to engage with a button 20, said button being passed through the tongue or loop, so that the stud 21 of such button will lie against the extremity of the tongue. The hinge or locking member 16 is then swung downwardly, so that the cross-bar 19 rests against the stud 21 on the opposite side from that bearing against the 100

end of the loop, and the peculiar formation of the locking member permits the sides 17 17 thereof to lie back of the vertical plane of the sides of the tongue, the point of juncture 5 of the cross-bar with the side portions of the locking member resting against the shoulders 11 11, formed on the tongue, the construction being such that the garment or the like will be securely held or clasped. When it is 10 desired to release the button, it is only necessary to press upon the sides of the body portion of the fastener, which will permit the locking member to be readily disengaged from contact with the spring sides of the device, and the button may then be easily slipped 15 out from engagement with the tongue.

While the drawings illustrate a fastener especially designed as a hose-supporter, it will of course be understood that it may be 20 readily applied and adapted for other and various uses.

Having thus described my invention, I claim as new and desire to secure by Letters Patent—

25 1. A fastening device, comprising a main body portion formed with an elongated tongue, said tongue having shoulders formed in its sides, and a locking member hinged to the main body portion, said locking member 30 being approximately U-shaped, and having a cross-bar which is designed to rest on the shoulders of the sides of the tongue, substantially as set forth.

2. A fastening device, comprising a body portion formed of a single piece of material, the ends of the material being connected by a tubular sleeve, an elongated tongue formed of a loop at one extremity of the body portion, the sides of said tongue having shoulders 35 formed therein, and a locking member hinged to the body portion at the open end of the tongue, said locking member having a

curved cross-bar formed at its free end, which bar is designed to bear against the shoulders formed in the sides of the loop when the device is in its operative position, substantially 45 as set forth.

3. A fastening device, comprising a body portion formed of a single piece of wire, the ends of said body portion being connected by 50 a tubular sleeve, a relatively long tongue portion formed on said body portion, the wire from which the body portion is formed having a compound bend or curve above the tongue portion, and a locking member hinged 55 to the body portion of the fastener at the open end of the tongue, said locking member having a cross-bar formed integral therewith, said bar being bent inward and set at an angle to the sides of the member, the construction being such that when it is in its locking operative position the cross-bar will engage with a button or stud and coöperate with the end of the tongue to secure a garment or the like upon said stud, substantially as set forth. 60

4. A fastening device, comprising a body portion formed with a tongue member, and a locking member hinged to the body portion adjacent to the tongue, the lower portions of the sides of the locking member being bent 70 outward at an angle to the main portion of the sides, and a cross-bar formed at the extremities of the angular lower portions, said bar being designed to coöperate with the end of the tongue to secure a garment or the like 75 upon a stud or button.

In testimony whereof I have signed my name to this specification in the presence of two subscribing witnesses.

FRANCES C. McDONALD.
